UNITED STATES PATENT OFFICE

2,459,013

REAMER CLAMP FOR RAILROAD CAR AXLES

Edward L. Bowen, McComb City, Miss.

Application April 14, 1947, Serial No. 741,402

3 Claims. (Cl. 77—13)

1

This invention relates to a device for reconditioning lathe center countersinks in railroad car axles. This is a necessary operation to insure a proper reconditioning of the journal bearings and wheel seats.

The principal object of this invention is the provision of a clamp which is adapted to hold a boring or reaming tool in proper alignment for boring, countersinking, or reaming the countersinks for lathe centers in railroad car axles. The clamp herein claimed is a handy demountable device which is self-aligning and which automatically holds the boring or reaming tool in alignment with the longitudinal axis of the axle.

A preferred embodiment of this invention is shown in the accompanying drawing in which—

Fig. 1 is a side view thereof, partly in section, said embodiment being shown clamped in place on a car axle and holding a countersinking tool in appropriate alignment for a countersinking operation.

Fig. 2 is a top view thereof;

Fig. 3 is an end view thereof, said view being also a sectional view on the line 3—3 of the car axle; and

Fig. 4 is a perspective view of the moving parts of the clamp.

The clamp herein claimed is provided with a frame 10 which comprises a pair of spaced plates 11 and 12, respectively, held in appropriate position relative to each other by means of U-shaped plates or brackets 13 and 14, respectively, and bolts and spacers 15 and 16, respectively. It will be noted that side plates 11 and 12 are each provided with a large substantially ellipse-shaped opening 20. The purpose for which this opening is designed will hereinafter become apparent.

Supported by the frame are bell cranks 21, each bell crank being mounted on a fulcrum 22 which is connected to the side plates 11 and 12. The outer free ends of bell cranks 21 are connected to longitudinally extending bars 23 and the inner free ends of said bell cranks are connected to draw bars 24. It will be observed that inasmuch as the several bell cranks 21 are identical with each other, bars 23 will necessarily always lie on parallel lines with their respective draw bars 24 and all movement between said bars will necessarily be parallel movement.

To control the relative movement between bars 23 and draw bars 24, a plate 30 is provided, said plate being connected to the free ends of draw bars 24 by means of bolts 31. This plate is provided with a center hole which is threaded to receive a screw 32. At one end the screw abuts

block 33 connected to frame 10, and at the opposite end the screw is provided with a spoked handle 35. Reference to Fig. 1 will disclose that screw 32 comprises a hollow member which is rotatably mounted on a cylindrical member 34. This cylindrical member is connected to block 33 at one end, and at its free end it is provided with a collar 31. The collar and the block prevent longitudinal movement of screw 32. It will be understood that when the handle is turned in a direction forcing the screw against the block 33, the draw bars 24 will be pulled toward the handle and the bars 23 will be caused to move in the opposite direction. By the same token rods 23 and 24 will move toward each other and the net effect will be to bring rods 23 closer to the center of the device under discussion.

It will be noted that the free ends of rods 23 which are situated opposite the free ends of rods 24 are provided with flanges 36 which cooperate with each other to provide V-shaped clamping or gripping members for gripping the journal bearing portions 40 of axles 41. A clamping action between said V-shaped members and journal bearing portions 40 takes place when handle 35 is turned as aforesaid. In consequence of clamping members 36 to journal bearing portion 40, the entire frame 10 and especially its block 33 and the screw 32 which bears against said block, are lined up centrally of the axle.

Cylindrical member 34 is internally threaded and a correspondingly threaded hole in block 33 is provided as a continuation of the threaded hole in member 34. A second screw 50 extends through the threaded holes in members 34 and 33, and it will be noted that this screw is provided with a handle 51 corresponding to handle 35 of the first-mentioned screw. Longitudinal movement of screw 50 toward or away from the axle may be effected by turning handle 41. The inner end of screw 50 is reduced to engage a socket in the housing of an air motor 55. The air motor 55 holds and actuates a tool 56 which in the drawing is a combination boring and countersinking tool. When the cutting end of the tool is inserted into the countersink 57 of the axle and the motor housing is in engagement with the reduced end of screw 50, both the tool and the motor housing are brought into alignment with the longitudinal axis of the axle. The bit 56 may be caused to bite into the countersink 57 by simply turning handle 51 and causing thereby an inward movement of screw 50 against the housing of the air motor 55.

The invention herein claimed is broader than

the specific embodiment thereof which is shown in the drawing. For example the present device is not limited to the use of an air motor. It may be used in conjunction with an electric drill or any similar device. Although a combined drill and countersink is shown in the drawing, the device may be used in conjunction with any other type of appropriate cutting tool as for example a reamer or a drill bit. Although a V-shaped gripping member 36 is shown on the drawing, 10 other designs of clamping means may be employed to clamp the device to the journal bearing portion of the axle. Other variations may be incorporated into the present device without departing from the essential principles and features 15 of the invention.

I claim:

1. In a device of the class described, a clamping jaw, a rod supporting said jaw, means for supporting said rod for movement parallel to itself, and means for applying force to said rod which is always substantially at right angles to the length of the rod.

2. In a device of the class described, a clamping jaw, a rod supporting said jaw, a pair of bell-

crank levers, the ends of one arm of said levers being connected to said rod for movement parallel to itself, and means connected to the other ends of said levers to move said rod parallel to itself and to exert a pressure on it substantially always at right angles to its length.

3. In a device of the class described, a clamping jaw, a rod supporting said jaw, a pair of bell crank levers with substantially rectangular arms, one pair of arms dependent and another pair of said arms substantially horizontal and connected to said rod, and means connected to the dependent arms to move them to move the rod parallel to itself and to exert a thrust on it which is always substantially at right angles to the rod.

EDWARD L. BOWEN.
